UNITED STATES PATENT OFFICE.

GEORGE ELLIOTT AND HAROLD M. WALKER, OF KANSAS CITY, MISSOURI, ASSIGNEES,
BY MESNE ASSIGNMENTS, TO INTERNATIONAL PATENTS DEVELOPMENT COMPANY,
A CORPORATION OF DELAWARE.

EAR-FEEDING APPARATUS.

Application filed August 9, 1924. Serial No. 731,046.

To all whom it may concern:

Be it known that we, GEORGE ELLIOTT and HAROLD M. WALKER, citizens of the United States, residing at Kansas City, in the county of Jackson and State of Missouri, have invented certain new and useful Improvements in Ear-Feeding Apparatus, of which the following is a specification.

This invention relates to pail assembling machines, and more particularly to an apparatus for automatically feeding the handle-receiving ears to the machine which positions these ears upon the pail.

In the patent to William Spain, No. 1,423,693, granted July 25, 1922, is disclosed a machine for positioning the ears upon the pail. In this apparatus a pair of rotary conveyors are intermittently operated to bring a pair of ears against diametrically opposite sides of a pail, and then the pail is pushed or translated longitudinally to engage the ends of the ears under the flange of the pail-cover.

According to the present invention automatic means are provided to feed the ears in pairs, to the positioning machine during the interval while a previously provided pair of ears are being positioned under the cover flange. Specifically, a pair of magazine chutes filled with ears, which feed down by gravity, are positioned so that one chute delivers to each ear-positioning conveyor. Reciprocating fingers push an ear from each chute into the receiving recess in the corresponding conveyor, and these feeding fingers are simultaneously operated from the means which translates the pail to engage the previously provided ears under the flange of the pail cover. In this way the complete ear-positioning operation is made continuous and automatic.

The particular objects and advantages of this invention will be more apparent from the following detailed description of one improved form of apparatus embodying the principles of this invention.

In the accompanying drawings:

Fig. 1 is a side elevation of the complete machine.

Fig. 2 is a vertical section taken substantially on the line 2-2 of Fig. 1, the ear-feeding mechanism being shown in side elevation.

Fig. 3 is a partial plan view of portions of the operating mechanism. 55

Fig. 4 is a plan view, on an enlarged scale, of the ear-feeding mechanism, this view being taken substantially on the line 4-4 of Fig. 2.

Fig. 5 is a vertical section through this feeding mechanism on a still larger scale, taken substantially on the line 5-5 of Fig. 4.

Fig. 6 is a transverse vertical section, taken substantially on the line 6-6 of Fig. 4. 65

Fig. 7 is a similar section taken substantially on the line 7-7 of Fig. 4.

Fig. 8 is a fragmentary view in perspective of the upper portion of the pail, showing a handle-receiving ear in its applied position, the upper edge of said ear being inserted between the body of the pail and the depending flange of the pail cover. 70

Referring first more particularly to Figs. 1, 2 and 3, a pair of rotary conveyors designated generally as 1 and 2, are mounted on parallel horizontal shafts 3 and 4 supported on a suitable framework 5. Each of the conveyors 1 and 2, which are substantial duplicates of one another, comprises an inner drum 6 fixedly supporting a pair of similar cylindrical disks 7 and 8, spaced from one another. Each pair of disks 7 and 8 is provided with mating semi-cylindrical recesses 9 and 10, there being a series of 85 these recesses, here shown as eight, spaced at equal intervals about the periphery of the conveyor. The conveyors 1 and 2 are rotated in unison in opposite directions by means of the inter-meshing gears 11 and 12 secured to the shafts 3 and 4 respectively, and the shafts 3 and 4 are so spaced that when a pair of the arcuate recesses in the periphery of the conveyors are opposed to one another with their centers in the horizontal plane passing through the axes of shafts 3 and 4, these mating recesses will provide a substantially cylindrical support for one of the pails 13. 90

The conveyors 1 and 2 are preferably operated intermittently, so that as each cylindrical support for the pail body is formed, as just described, the rotation of the conveyors is interrupted for a time sufficient to permit other intermittently operated mechanism, hereinafter described, to position 100

the handle-receiving ears beneath the flange of the pail cover. In the construction here shown, a driving wheel 14 is secured to the gear 12, the wheel 14 being provided with a series of spaced radial slots 15 extending inwardly from the periphery of the wheel, there being as many slots 15 as there are pail-receiving recesses 9. A gear 16, keyed to a shaft 17 mounted in the frame 5 directly below the shaft 4, has secured to one of its faces at diametrically opposite points, a pair of driving rollers 18. As the gear 16 is continuously rotated, one of these rollers 18 will engage in one of the slots 15 and 10 rotate the wheel 14 and the conveyors through an arc equal to the distance between two of the adjacent pail-receiving recesses 9. The rotation of the driving wheel 4 and of the conveyors will then cease until the 15 next roller 18 comes into engagement with the next slot 15 in the driving wheel. A driving pinion 19 on driving shaft 20, meshes with and continuously drives the gear 16. It will be noted that as the driving 20 shaft 20 is continuously rotated, the two pail conveyors 1 and 2 will be intermittently rotated in opposite directions, halting for certain limited period eight times during each 25 revolution.

30 A radially slidable ear-retaining chuck 21 is mounted in the disk 12 beneath each pail-receiving recess 9. The outer ear-supporting surface of this chuck is recessed to receive the navel of the ear, (as shown at 22 Fig. 5), and preferably a permanent magnet 23 is employed to normally hold the ear in place in the chuck. A cam projection 24 on each chuck is adapted to project the chuck and ear radially outward against the action of a 35 retracting spring, (not shown).

40 A lever 25 centrally pivoted at 26 on frame 5, has at one end a pin 27 engaging in cam slot 28 in the cam wheel 29 keyed to shaft 17. The opposite end of lever 25 connects at 30 with a plunger 31 adapted to be reciprocated toward and from the covered end of pail 13, as shown more particularly in Fig. 3. A pair of cams 32 on plunger 31 45 cooperate with cams 24 to project the ear-holding chucks 21 radially.

50 In operation, we will assume that the two conveyors 1 and 2 have halted temporarily, with a set of pail-receiving recesses 9 and 10 in each conveyor directly above the shafts 3 and 4. At this time an ear 33 is placed in each of the chucks 21. At the next rotation of the conveyors these recesses are carried forward 45° to a position, as shown in Fig. 1, where one of the pails 13, with its previously applied cover 34 in place thereon, is delivered into the pail-receiving recess in conveyor 1 from a pail-delivering chute 35. The next intermittent rotation carries this 55 pail downward to the position where it is gripped between the two conveyors 1 and 2 in the plane of the supporting shafts 3 and 4. During the interval while the conveyors 1 and 2 have ceased to rotate, and are holding the pail 13 at this point, the pin 27 enters the offset portion 36 of cam slot 28 70 in constantly rotating cam 29 and operates lever 25 to project the plunger 31 toward the covered end of the pail. As the plunger 31 moves forwardly, the cams 32 will first engage the cams 34 and project the ear-retaining chucks 21 and the ears 33 held thereby against the sides of pail 13. Further movement of plunger 31 will engage the cover 34 of the pail and push or translate the pail longitudinally so that the ends 80 of the stationarily held ears 33 will be projected beneath the down-turned flange 37 of cover 34. This position of the assembled parts is shown in Fig. 8. The plunger 31 is then retracted, as the pin 28 returns to the straight portion of cam slot 28, and upon the next rotation of the conveyors the assembled pail is dropped into the delivery chute 38 below the machine. All of the above is substantially as shown and described in 90 greater detail in the patent to Spain 1,423,693, referred to hereinabove and reference to this patent should be made for a more complete disclosure of this portion of the machine and its operation.

95 The present invention relates more particularly to the combination with the above machine of a means for automatically feeding the ears to the ear-holding chucks 21 of the positioning machine as described above. Mounted above and to one side of each conveyor is an ear-holding chute or magazine 39. These two chutes are substantial duplicates of one another and a description of one will suffice for both. The chute 100 39 is mounted on a bracket 40 projecting upwardly from the machine frame 5, so that the delivery end 41 of the chute will lie substantially in the vertical plane passing through the shaft 3 or 4. Extending throughout the 105 entire length of the chute is a lower slideway 42, in which a plurality of the ears 33 are placed and feed downwardly automatically by gravity. The upper end of slideway 42 is cut away at the top, as shown at 43 Fig. 4, so that the ears 33 may be manually fed into the chute at any desired time, or fed thereto in any other suitable manner. At the lower delivery end of the chute, a finger 44 is centrally pivoted between lugs 45 on 110 the bottom of the chute, and has its upper end 46 projecting into the path of the downwardly moving ears to normally prevent the passage of one of these ears from the delivery end of the chute. A spring 47 engages the rear end of finger 44 to normally hold its forward end 46 in the pathway of the ears.

115 A pair of slides 48 and 49 reciprocate in a slideway 50 formed in the lower end of 120

125

130

chute 39 above the lower ear-holding slide-way 42. A bearing block 51 is pivoted at 52 on the upper side of slide 48, and an ear-delivering finger 53 is centrally pivoted at 54 in block 51. A compression spring 55, located between the rear end of finger 53 and the slide 48, holds the forward forked end 56 of the finger in engagement with the navel of one of the ears 33. The plates 57 forming the upper sides of slideway 50, are held yieldably down in contact with the slide 48 by means of springs 58 surrounding the bolts 59. In this way the slide 48 is held firmly but yieldably in place in any position it may assume. A link 60 is pivoted at 61 to a projection 62 on finger 53, and at its other end is pivoted at 63 in a projection 64 rising from the upper side of slide 49. An adjusting screw 65 mounted in link 60 bears upon the upper rear end of finger 53, and adjustably limits the downward ear-engaging position of the forward forked end 56 of finger 53.

In operation, the upper slide 49 is reciprocated in the slideway 50 by a means hereinafter described. When the slide 49 is moved downwardly, it will through the link 60, move the lower slide 48 and finger 53 downwardly, ejecting an ear 33 past the yieldable detent 46 into one of the ear-holding chucks 21. The following ear 33, sliding down the chute by gravity, will be retained in the chute by the yieldable detent 46. Upon the return movement of slide 49, the link 60, through projection 62, will lift the forward end of finger 53 against the action of compression spring 55, so that the forked end 56 of the finger will pass over the ear 33 now at the lower end of the chute 40 on the return stroke of the finger. The spring pressed plates 57 exert a drag on the slide 48 to insure the lifting of the finger 53 as above described.

A feed-operating lever 66 is pivoted at 45 its lower end 67 in a bracket 68 projecting from frame 5, and the upper end of the lever is connected by link 69 with the projection 70 on the operating slide 49. Near its lower end, lever 66 is pivoted at 71 to one end of a cross head 72, the similar lever 66 for the other ear-feeding unit being pivoted to the other end of the cross head 72. The cross head 72 is centrally secured at 73 to the outer end of the squared slide shaft 55 74 which carries the plunger 31.

It will now be seen that during the operation of the ear-positioning machine first described, when the conveyors have temporarily halted and the plunger 31 is being moved inwardly by cam 29 to position one pair of ears 33 beneath the flange 37 of pail cover 34, the levers 66 will be simultaneously operated to impart a forward working stroke to the ear-feeding slides 48 and 49 65 and the mechanism operated thereby as de-

scribed above. This will position a new pair of ears 33 in the ear-holding chucks 21 then uppermost in the ear-positioning machine. It will be noted that in the continuous operation of this machine, four separate automatic operations will simultaneously take place at four successive stations in the machine, every time that the rotation of the conveyors 1 and 2 is temporarily halted.

At the first station directly above the shafts 75 3 and 4, a pair of ears 33 are delivered to the ear-holding chucks 21. At the second station a pail 13 is delivered into one of the recesses 9. At the third station a pail 13 is translated longitudinally to engage 80 the ears 33 beneath the flange 37 of cover 34. At the fourth station an assembled pail is dropped into the delivery chute 38.

It will be noted that the operation of the machine to perform all of these functions 85 is continuous and entirely automatic. It is only necessary that the drive shaft 20 be continuously rotated, and the pails 13 and ears 33 be supplied to the chutes 35 and 39 respectively at convenient intervals.

While one specific embodiment of the invention has been described, it will be obvious that various modifications in structure might be made without departing from the spirit of the invention. All such modifications are therefore contemplated as coming 95 within the scope of the appended claims.

We claim:

1. An apparatus for feeding pail ears to an ear manipulating machine, comprising a chute having an open lower end through which the ears would normally discharge by gravity, yieldable means engaging the lowermost ear to hold the ears within the chute, and means for positively forcing this 100 ear from the chute past the first mentioned means, the yieldable means then engaging the next succeeding ear.

2. In an apparatus for positioning ears on pails, a rotary conveyor having a series 110 of ear holding pockets, a magazine chute having an open lower end with which the pockets are successively brought into register, and means timed with the rotary conveyor for ejecting the ears one by one from 115 the chute into the pockets.

3. In an apparatus for positioning ears on pails, a rotary conveyor having a series 120 of ear holding pockets, a magazine chute having an open lower end with which the pockets are successively brought into register, means normally holding the ears within the chute, and means timed with the rotary conveyor for ejecting the ears one by one into the pockets.

4. In an apparatus for positioning ears on pails, a rotary conveyor having a series of ear holding pockets, a magazine chute having an open lower end with which the pockets are successively brought into regis- 130

- ter, driving means for intermittently advancing the conveyor to successively bring the pockets to rest at the foot of the chute, and means actuated from the driving means for successively ejecting the ears one by one from the chute into the pockets during the intervals when the pockets are at rest.
5. In an apparatus for positioning ears on pails, a rotary conveyor having a series 10 of ear holding pockets, a magazine chute having an open lower end with which the pockets are successively brought into register, driving means for intermittently advancing the conveyor to successively bring 15 the pockets to rest at the foot of the chute, means for holding the ears within the chute while the pockets are in motion, and means actuated from the driving means for successively ejecting the ears one by one from 20 the chute into the pockets during the intervals when the pockets are at rest.
6. An ear feeding mechanism comprising a chute having a slide-way for the ears, a second slideway in the chute parallel to the 25 first mentioned slideway and adjacent its delivery end, and a reciprocating member in the second slideway including means for engaging an ear on its operative stroke and delivering it from the chute.
- 30 7. An ear feeding mechanism, comprising a chute having a slide-way for the ears, a second slideway in the chute parallel to the first mentioned slideway and adjacent its delivery end, a reciprocating member in the 35 second slideway including means for engaging an ear on its operative stroke and delivering it from the chute, and a yielding detent for normally preventing the passage of the ears from the chute.
- 40 8. An ear feeding mechanism, comprising a chute having a slide-way for the ears, a second slideway in the chute adjacent its delivery end, a reciprocating member in the 45 second slideway, a pivoted finger mounted on the reciprocating member adapted to engage an ear on its forward stroke, and means for reciprocating the member.
- 50 9. An ear feeding mechanism, comprising a chute having a slide-way for the ears, a second slide-way in the chute adjacent its delivery end, a reciprocating member in the 55 second slide-way, a pivoted finger mounted on the reciprocating member adapted to engage an ear on its forward stroke, a reciprocatory driving means, and a link connection between this means and the finger, whereby on a forward stroke of the driving means an ear will be engaged and ejected from the chute, and upon the return stroke 60 the finger will be lifted to ride over the ear now in position at the end of the chute.
- 65 10. An ear feeding mechanism, comprising a chute having a slide-way for the ears, a second slide-way in the chute adjacent its delivery end, a reciprocating member in the 70 second slide-way, a pivoted finger mounted on the reciprocating member adapted to engage an ear on its forward stroke, a reciprocatory driving means, and a link connection between this means and the finger, whereby on a forward stroke of the driving means an ear will be engaged and ejected from the chute, and upon the return stroke 75 the finger will be lifted to ride over the ear now in position at the end of the chute, and a yielding detent at the exit end of the chute for normally preventing the passage of an ear from the chute unless positively ejected by the finger.
- 80 11. In combination with a machine for positioning ears on pails, means for feeding the ears to the machine comprising a pair of magazine-chutes, and means operated from the ear-positioning mechanism for automatically feeding a pair of ears from 85 the chutes to the machine at fixed intervals.
- 90 12. In combination with a machine for positioning ears on pails, means for feeding the ears to the machine comprising a pair of slide-ways, a reciprocating device cooperating with each slideway to deliver an ear to the positioning machine and means operated from the machine for actuating the delivering devices.
- 95 13. The combination with a machine for positioning ears on pails, comprising a pair of conveyors, means to intermittently operate the conveyors to bring a pair of ears against opposite sides of the pail, and means operating during the intervals when the conveyors are at rest to position the ears beneath the cover flange of the pail, of means for feeding the ears to the machine, and means for actuating this means from the positioning mechanism during the intervals 100 of rest of the conveyors.
- 105 14. The combination with a machine for positioning ears on pails, comprising a pair of conveyors, means to intermittently operate the conveyors to bring a pair of ears against opposite sides of the pail, and means operating during the intervals when the conveyors are at rest to position the ears beneath the cover flange of the pail, of means for feeding the ears to the machine comprising a pair of magazine-chutes, and means actuated from the positioning mechanism for feeding a pair of ears from the chutes to the machine during the intervals of rest 110 of the conveyors.
- 115 15. The combination with a machine for positioning ears on pails, comprising a pair of conveyors, means to intermittently operate the conveyors to bring a pair of ears against opposite sides of the pail, and means operating during the intervals when the conveyors are at rest to position the ears beneath the cover flange of the pail, of means for feeding the ears to the machine comprising a pair of magazine-chutes, and means 120 actuated from the positioning mechanism for feeding a pair of ears from the chutes to the machine during the intervals of rest of the conveyors.
- 125 16. The combination with a machine for positioning ears on pails, comprising a pair of conveyors, means to intermittently operate the conveyors to bring a pair of ears against opposite sides of the pail, and means operating during the intervals when the conveyors are at rest to position the ears beneath the cover flange of the pail, of means for feeding the ears to the machine comprising a pair of magazine-chutes, and means 130

- actuated from the positioning mechanism for feeding a second pair of ears to the machine from the chutes, while a first pair is being positioned beneath the pail-cover.
- 5 16. In apparatus for positioning ears on pails, intermittently operating conveying mechanism which temporarily halts at successive stations, and automatically operating mechanism for feeding ears thereto at the first station, a pail thereto at the second station, positioning the ears on the pail at the third station, and delivering the assembled pail from the machine at the fourth station.
- 10 17. In apparatus for positioning ears on pails, intermittently operating conveying mechanism having a series of similar ear and pail holding supports, each of which temporarily halts at successive stations, means for simultaneously and automatically delivering ears to the conveyor at one station, a pail at the next station, positioning ears on a pail at a third station, and ejecting an assembled pail at the last station.
- 15 18. In apparatus for positioning ears on pails, a pair of similar intermittently operating conveying mechanisms, having pail holding recesses adapted to mate at one station to engage opposite sides of a pail, an ear holder in each pail holding recess, and means for automatically delivering a pair of ears to the ear holders at a preceding station.
- 20 19. In apparatus for positioning ears on pails, a pair of similar intermittently operating conveying mechanisms, having pail holding recesses adapted to mate at one station to engage opposite sides of a pail, an ear holder in each pail holding recess, and means for automatically and simultaneously delivering an ear to each of the ear holders at a preceding station.
- 25 20. In an apparatus for positioning ears on pails, a pair of mating conveyors each adapted to embrace one side of a pail and each embodying an ear-holding recess, means to feed an ear to each recess, and means to subsequently feed a pail to the mating conveyors.
- 30 21. In an apparatus for positioning ears on pails, a pair of mating conveyors each adapted to embrace one side of a pail and each embodying an ear-holding recess, means to feed an ear to each recess, means to feed a pail to the mating conveyors in contact with the ears, and means to impart relative movement to the pail and ears, while held by the conveyors, to secure the ears on the pail.
- 35 22. In an apparatus for positioning ears on pails, a pair of conveying mechanisms, means for separately feeding ears one to each conveying mechanism at regular intervals, the subsequent movement of the conveying mechanisms bringing this pair of ears into register with opposite sides of a pail, and means for positioning the ears on the pail.
- 40 23. In an apparatus for positioning ears on pails, a pair of conveying mechanisms, having pail-holding recesses adapted to mate at one station to engage opposite sides of a pail, there being an ear holder in each pail-holding recess, and automatic means for delivering ears to the ear-holders before the rail is received in the mating recesses.
- 45 24. In an apparatus for positioning ears on pails, a pair of conveying mechanisms, having pail-holding recesses adapted to mate at one station to engage opposite sides of a pail, there being an ear holder in each pail-holding recess, and automatic means for delivering ears to the ear-holders before the rail is received in the mating recesses, and means to impart relative movement to the pail and ears, while held by the conveyors, to position the ears upon the pail.
- 50 25. An apparatus for feeding pail ears to an ear positioning machine which includes a moving conveyor having ear receiving portions, comprising a magazine for the ears, and means timed with the conveyor for delivering ears from the magazine only when the ear-receiving portions are in ear-receiving position.
- 55 26. An apparatus for feeding pail ears to an ear positioning machine which includes a holder for the pail, having ear-receiving portions, a pair of ear-feeding magazines, and means for delivering an ear from each magazine to the ear-receiving portions of the pail holder.
- 60 27. An apparatus for feeding pail ears to an ear positioning machine which includes a holder for the pail, having ear-receiving portions, a pair of ear-feeding magazines, and delivering means on each magazine which are synchronously operated whereby a pair of ears for each pail are delivered to the pail-holder, one ear from each magazine.
- 65 28. In a machine for placing ears on cans, an ear feeding device comprising a chute through which the ears pass in succession, means for normally retaining the ears within the chute, and means for positively ejecting the ears one by one from the chute past the retaining means.

GEORGE ELLIOTT.
HAROLD M. WALKER.
